UNITED STATES PATENT OFFICE.

ARTHUR G. HATCH, OF DULUTH, MINNESOTA.

FORM FOR CONCRETE BLOCKS AND METHOD OF REMOVING BLOCKS THEREFROM.

Application filed November 2, 1921. Serial No. 512,207.

To all whom it may concern:

Be it known that I, ARTHUR G. HATCH, a citizen of the United States, residing at Duluth, in the county of St. Louis and State 5 of Minnesota, have invented certain new and useful Improvements in Forms for Concrete Blocks and Methods of Removing Blocks Therefrom, of which the following is a specification.

10 My invention comprises new and improved forms for concrete blocks and more particularly to forms having removable portions adapted to aid in removing blocks from the forms. It further consists in a method of 15 removing blocks from such forms.

The various types of block forming machines now in general use have relatively low capacity due to the fact that the block must remain in the machine or mold until it 20 has taken a large part of its set. It is difficult to remove the green blocks without breaking them. Efforts have been made to secure quantity production by forming blocks in large gang molds but with these 25 molds also, the blocks must remain in place until well set.

It is an object of the present invention to provide molds having removable sections and which sections are adapted to facilitate 30 the removal of the blocks.

It is a further object to provide molds of this character adapted to form grout grooves or other markings in the sides of the blocks, the portions of the form entering the markings aiding in removing the blocks.

It is an additional object to provide an improved method of removing the blocks with such a form.

Other and further objects will appear as 40 the description proceeds.

Broadly, my invention comprises a gang form or a form adapted for the simultaneous casting of a number of blocks, this form having fixed members and removable members, the latter having portions adapted to 45 extend within the contour of the blocks.

In the preferred form, these portions form grout grooves. It is by means of these portions extending into these blocks that the 50 blocks may be removed by the removal of the removable members of the form.

In the preferred form, the removable members consist of one section forming the dividing form between two adjacent blocks

and of a second section rigidly connected at 55 right angles thereto, the second section forming one end of the adjacent blocks.

I have illustrated a preferred embodiment 60 of my invention in the accompanying drawings, in which—

Figure 1 is a plan view of a gang mold embodying my invention;

Figure 2 is a section taken upon line 2—2 of Figure 1;

Figure 3 is a section taken upon line 3—3 65 of Figure 1; and

Figure 4 is a perspective view of one of the removable form members.

The form as shown in Figure 1 comprises the removable end members 6 and 7, the side 70 members 8 and 9, and a fixed dividing member 10, the latter being best shown in Figure 2.

In the preferred form, the side member 9 is formed integrally with the bottom member 11. The central dividing member 10 comprises two upwardly extending portions which are integral with the member 11. The member 11 is formed to give the desired 75 contour to the blocks.

In the form shown, each block is provided 80 with the narrow flange 12 and wide flange 13, adjacent blocks being oppositely faced so that the wide flanges are adjacent each other. As shown in Figure 3, the blocks are provided 85 with thickened end ribs 14 which join the two flanges.

The removable form members 15 shown in Figure 4, have the portions 16 adapted to extend between the wide flanges on adjacent 90 blocks. They are further provided with cross portions 17 adapted to form an end of each of the two adjacent blocks. Each of these portions 16 and 17 is provided with an enlarged rib 18 which serves to form a grout 95 groove in the edge faces of the block. The member 15 is further provided with the flange 19 upon the lower edge of its portion 16. This flange aids in lifting the blocks in removing them from the molds. As shown 100 in Figure 1, the outer face of each portion 17 of the movable member has its enlarged rib 18 cut away at its center to permit the insertion of the end of the portion 16 of the adjacent removable member 15. The adjacent members are thus interlocked.

In the use of this form of molds, the movable members are all assembled in place in

the fixed portions of the mold. Concrete is then poured on to the mold and smoothed off level with the upper edges of the dividing portions of the mold. After it has been 5 allowed to partly set, sufficiently for handling, the end member 6 of the mold is removed. Then by grasping the exposed end of the first removable member, it may be tilted in the manner shown in Figure 3, thus 10 lifting the two blocks from the mold. Once lifted clear of the fixed portions of the mold, they may be removed and placed upon racks or other suitable drying means. As 15 they are then exposed on all sides to the air, they cure more rapidly than if they were allowed to remain in the molds. Further, due to the assistance which the removable members 15 afford, the blocks may be removed from the mold much more quickly 20 and in a greener state than would be possible were the blocks handled directly.

I am aware that my invention may be modified for application to varying conditions and for use in the formation of differing contour and it is my intention to cover 25 all modifications coming within the spirit and scope of the appended claims.

I claim:

1. The method of removing concrete 30 blocks from molds comprising moving the block away from a fixed part of the mold

by means of a portion of the mold forming lateral faces of the block.

2. The method of removing concrete blocks from molds comprising moving the 35 block away from a fixed part of the mold by means of a movable part of the mold, said movable part having portions extending within the contour of the block.

3. A mold for forming concrete blocks 40 comprising fixed members and removable members, the latter comprising T-shaped sections adapted to form intersecting faces of each of two adjacent blocks.

4. A mold for forming concrete blocks 45 comprising fixed members and removable members, the latter comprising T-shaped sections adapted to form intersecting faces of each of two adjacent blocks, said sections 50 having portions adapted to extend within the contour of the block.

5. A mold for forming concrete blocks comprising fixed members and removable members, the latter comprising T-shaped 55 sections adapted to form intersecting faces of each of two adjacent blocks, said sections having portions adapted to form grout grooves in the blocks.

Signed at Duluth, Minnesota, this 24 day of October, 1921.

ARTHUR G. HATCH.
